(57) **CLAIM**

I claim the ornamental design for an bandolier pack, as shown and described.

DESCRIPTION

FIG. 1 is a rear elevation view of the bandolier pack as shown and described;

FIG. 2 is a front elevation view thereof;

FIG. 3 is a left side elevation view thereof;

FIG. 4 is a right side elevation view thereof;

FIG. 5 is a perspective view thereof; and,

FIG. 6 is a flat elevation view of the upper front portion thereof, showing an open zipper compartment and an identification card pocket with a clear window and cover flap open, as shown.

The broken line showing of environment in the drawings is included for the purpose of illustrating only and forms no part of the claimed design.
